INTERNAL-COMBUSTION ENGINE

Cecil B. Davis and Wilbur M. Arthur,
Kingman, Ariz.

Application May 23, 1945, Serial No. 595,314

5 Claims. (Cl. 123—51)

1

The invention relates to internal combustion engines, and has for one of its objects to provide an improved apparatus of this character having opposed cylinders with oppositely acting reciprocating pistons in each thereof, and relatively simple mechanism for translating the reciprocating motion of the pistons into rotary motion, with minimum bearing loads.

A further object of the invention is to provide an engine having relatively few moving parts and in which the heavy crankshaft, connecting rods and bearings of conventional engines are eliminated, with consequent reduction in weight and cost of manufacture, and increased efficiency.

While the principles of the invention are equally applicable to engines employing either the lighter hydrocarbons as fuel and spark ignition thereof, or those using the heavier oils and operating on the Diesel principle, for purposes of disclosure an engine of the first type is illustrated in the accompanying drawings forming a part of this specification. In these drawings certain minor elements, such for example as the fuel supply and exhaust conduits, shrouds for directing cooling air around the cylinders, etc., have been omitted, since they may take a variety of more or less conventional forms and are not essential to an understanding of the principles of the invention.

In the said drawings:

Figure 1 is a side elevational view, partly broken away and in section, of a typical engine constructed and arranged in accordance with the invention;

Fig. 2 is a horizontal sectional view on approximately the plane indicated by the line 2—2 of Fig. 1, looking down; and

Figs. 3 and 4 are cross sectional views, taken respectively on approximately the planes indicated by the lines 3—3 and 4—4 of Fig. 1, looking in the direction of the arrows.

Referring more particularly to the drawings, the engine may be provided with suitable frame members 10 which fixedly mount a tubular member 11 providing a pair of axially aligned working chambers 12 and 13. These may be provided with conventional water jackets for water cooling, but are here shown as having a plurality of cooling fins 14 for dissipating heat to the surrounding atmosphere, as will be readily understood by those skilled in the art. Journalled upon the medial portion of the tubular member 11, as by antifriction bearings 15, is a pair of complementary longitudinally spaced cam elements 16, providing between them a sinusoidal cam groove

17. These elements are surrounded by and secured to a rotor sleeve 18 which may serve as a pulley for engagement by a V-belt or other suitable means whereby the power may be transmitted from the engine. The rotor 18 may also carry fans or blowers 19 which, in conjunction with appropriate shrouds (not shown) direct cooling air to and around the working cylinders 12 and 13.

A hollow piston rod 20 is disposed within the cylinder member 11 co-axially therewith, and its respective end portions rigidly carry the outer pair of pistons 21 and 22. The outer faces of these pistons are recessed as at 23 and 24, and the extreme ends of the rod 20 carry heads 25 and 26 disposed within the respective recesses 23 and 24, and having ports 27 and 28 affording communication between such recesses and the interior of the piston rod, all as will be clear from Fig. 2. The heads 25 and 26 carry flexible or resilient valve disks 29 and 30 for controlling communication between the recesses 23 and 24 and the respective working cylinders 12 and 13, as will appear more fully below.

The medial portion of the piston rod 20 rigidly carries a pair of oppositely extending studs 31 which project through slots 32 formed in the wall of the cylinder member 11, and into the cam groove 17 where they are preferably provided with anti-friction rolls 33. The studs may also carry similar rolls 34, working in the slots 32.

Surrounding the piston rod 20 and slideable relative thereto, is a sleeve 35 having longitudinal slots 36 to accommodate the studs 31, and rigidly carrying pistons 37 and 38 at its respective ends. This sleeve 35 also rigidly carries oppositely projecting studs 39, disposed at substantially right angles to the studs 31 (see particularly Fig. 4), and extending through slots 40 in the wall of cylinder member 11 into the cam groove 17. The end portions of these studs may be provided with anti-friction rollers 41 and 42 working in the said cam groove and in the slots 40 respectively. Since the cylinder member 11 of course is fixed, the slots 32 and 40 serve as guides for the rollers 34 and 42 and the studs 31 and 39 carrying them, which prevents rotation of the studs and pistons about the cylinder axis.

At the inner ends of the respective working chambers 12 and 13 the wall of the cylinder member 11 is provided with the series of circumferentially arranged exhaust ports 43 and 44, while at the outer ends of said chambers such wall is provided with the series of inlet ports 45 and 46. The open outer ends of the respective working

chambers are closed by removable caps or cylinder heads 47 and 48 which, as will be clear from Figs. 2 and 3, are spaced somewhat from the cylinder wall to provide the annular passages 49 and 50 communicating with the respective inlet ports 45 and 46. The exhaust ports 43 and 44 may be surrounded by a suitable exhaust conduit (not shown) for conducting the exhaust gases away. The wall of the hollow piston rod 20 is provided with a plurality of ports 51, aligned with the slots 36 of sleeve 35 and affording communication between the bore of the said rod and the space 52 within the cylinder member 11 between the inner pair of pistons 37 and 38. Since the engine illustrated is assumed to be of the spark-ignition type using carburetted fuel, a conventional spark plug 53 is shown for each of the working cylinders, and the fuel mixture may be supplied to the space 52 by conduits 54 leading from an appropriate carburetor. It will be understood however, that in the case of an engine intended to operate upon the Diesel principle, the spark plugs 53 will be replaced by suitable fuel injectors, and fresh air will be supplied to the space 52 through the conduits 54.

The operation of the engine is as follows:

Assuming the parts to be in the positions illustrated in the drawings, to start the engine the rotor 18 is turned in either direction by external power supplied either manually or by any suitable mechanical starter mechanism, which movement is transmitted by the cam 17 through the studs 31 and 39 to the piston rod 20 and the sleeve 35 respectively, causing the pistons 21 and 37 to recede from one another and the pistons 22 and 38 to approach one another. As the piston 22 is thus moved toward the left, as viewed in Fig. 2, upon its covering ports 46 it will create a partial vacuum in the space between such piston and the cap 48 which will cause the valve 30 to open and fuel mixture to be sucked into such space from the medial space 52 by way of the ports 51, the bore of the piston rod 20, and the ports 28. When the rotor 18 has completed a 90° movement the motions of the several pistons will be reversed by the cam action, and as the piston 22 now moves toward the right its valve 30 will be closed and the fuel mixture ahead of it compressed until the piston uncovers ports 46 whereupon the mixture will escape therethrough into the working chamber 13, between the pistons 22 and 38. Although at this time the exhaust ports 44 have been uncovered by the piston 38, the admission of fuel mixture through ports 46 occurs very close to the ends of the strokes of the pistons and as their motions are reversed almost immediately whereby they again cut off the ports 44 and 46, little if any of the mixture will escape through the exhaust ports. On the contrary, it will be trapped between the now approaching pistons and compressed by them, while at the same time the valve 30 will again open and admit a fresh charge to the space between it and cap 48. When the pistons 22 and 38 reach a position corresponding to the illustrated position of pistons 21 and 37, a spark from the plug 53 will ignite the compressed fuel mixture and the resulting explosion and expansion of gases will force the pistons 22 and 38 apart, which motions of course will be transmitted through the piston rod 20 and sleeve 35, studs 31 and 39, and cam 17 to the rotor 18.

In the meantime the pistons 21 and 37 have been going through the same cycle, a quarter revolution of the rotor behind the pistons 22 and 38.

38, and thus the engine will now be operating, with each cylinder firing twice for each revolution of the rotor. As the inner pistons 37 and 38 alternately uncover their respective exhaust ports 43 and 44 (which preferably occurs slightly in advance of the opening of the respective inlet ports 45 and 46 by the outer pistons 21 and 22) the burnt gases will escape through such exhaust ports, with the incoming charge from inlet ports 45 and 46 performing a scavenging action, as in the well known two-cycle principle.

Should the engine be employed for aviation purposes, a propeller may be mounted directly upon the rotor 18. The engine will run equally well in either direction, this depending solely upon the direction in which it is started.

What is claimed:

1. In an internal combustion engine, a pair of spaced co-axial working chambers; an outer pair of pistons, one in each chamber, having a piston rod rigidly connecting them together for unitary reciprocation; an inner pair of pistons, one in each chamber, rigidly connected by a sleeve surrounding said piston rod, and reciprocatable relative to the first pair of pistons, the two pistons in each chamber providing a combustion space between them; a rotor element, including a sinuous cam, journalled for rotation about the axis of and between said working chambers; and driving connections between said cam and said piston rod and sleeve respectively whereby reciprocations of the pairs of pistons will cause rotation of said element, the respective driving connections being disposed at substantially right angles to one another.

2. In an internal combustion engine, a pair of spaced co-axial working chambers; an outer pair of pistons, one in each chamber, having a piston rod rigidly connecting them together for unitary reciprocation; an inner pair of pistons, one in each chamber, rigidly connected by a sleeve surrounding said piston rod, and reciprocatable relative to the first pair of pistons in directions opposite thereto; a rotor element, including a sinuous cam, journalled on the working chambers for rotation about their axis; and driving members carried by said sleeve and piston rod respectively, at substantially right angles to one another, and engaging said cam whereby reciprocating movements of the pairs of pistons may be translated into rotary motion of the rotor element.

3. In an internal combustion engine, a cylinder member providing a pair of spaced co-axial working chambers, the portion of said cylinder member intermediate said chambers having a plurality of longitudinal slots; an outer pair of pistons, one in each of said working chambers, having a piston rod connecting them for unitary reciprocation; an inner pair of pistons, one in each chamber, rigidly connected by a sleeve surrounding said piston rod, and reciprocatable relative to the first pair of pistons in directions opposite thereto; a rotor element having a sinuous cam groove, journalled on the intermediate portion of the cylinder member for rotation about its axis; and driving members carried by said sleeve and piston rod respectively, at substantially right angles to one another, said driving members extending through said slots in the intermediate portion of the cylinder member and engaging in said cam groove, whereby reciprocating movements of the pairs of pistons may be translated into rotary motion of the rotor element.

4. In an internal combustion engine, a pair of

spaced co-axial working chambers; an outer pair of pistons, one in each chamber, having a hollow piston rod rigidly connecting them for unitary reciprocation, and providing a fuel conduit; a valve carried by each of said pistons for controlling communication between said hollow piston rod and the portion of the respective chambers lying outwardly of the pistons; an inner pair of pistons, one in each chamber, rigidly connected by a sleeve surrounding said piston rod and reciprocatable relative to the first pair of pistons in directions opposite thereto; a rotor element comprising a sinuous cam, journalled for rotation about the axis of and between said working chambers; driving connections between said cam and the respective pairs of pistons, whereby reciprocating movements of the latter will be translated into rotary motion of the rotor element; and means for supplying combustible mixture to said hollow piston rod.

5. In an internal combustion engine, a pair of

10
15

spaced co-axial working chambers; an outer pair of pistons, one in each chamber; a hollow piston rod rigidly connecting said pistons for unitary reciprocation, and providing a fuel conduit communicating with the respective chambers outwardly of said pistons; an inner pair of pistons, one in each chamber, rigidly connected by a sleeve surrounding said piston rod and reciprocatable relative to the first pair of pistons in directions opposite thereto; a rotor element comprising a sinuous cam, journalled for rotation about the axis of said working chambers; driving connections between said cam and the respective pairs of pistons, angularly disposed relative to one another, whereby reciprocating movements of the pistons will be translated into rotary motion of the rotor element; and means for supplying combustible mixture to said hollow piston rod.
